ABSTRACT OF THE DISCLOSURE

An apparatus and method for separating two-piece, hard-shell capsules in which a capsule is propelled at a high rate of speed through a chute until its trailing section is abruptly halted. Momentum of the leading piece of the capsule is such that it continues forward a distance sufficient to permit complete separation of the two-piece capsule sections.

BACKGROUND OF THE INVENTION

Although the use of two-piece, hard-shell capsules has been primarily directed to the pharmaceutical industry, there are a number of other industries using such capsules. In general, these capsules comprise two pieces which are telescoped together to form an enclosed container. These empty capsules are usually supplied to the various industries in a joined condition. In the pharmaceutical industry powder or pellets are introduced into the capsule after the sections are separated. The separation of these capsules would seemingly be considered to be an easy step inasmuch as the fit between the two capsule sections is relatively loose. In the prior art capsules of this general description are normally separated on automatic equipment utilizing a vacuum principle. In such apparatus a capsule is seated in a bore having an annular shoulder on which the slightly larger cap section rests. The bore is in communication with a vacuum means which draws the body from the cap. However, it has been found that in extremely fast automatic capsule filling equipment a vacuum means is not one hundred percent foolproof. Occasionally, cap and body sections are telescoped together to an extent whereby they are not easily separated. The amount of force that can be created by a vacuum technique is necessarily limited. Thus, jammed capsules have been experienced and although the loss of a capsule is not normally significant, the resulting shutdown of the jammed capsule filling equipment can cause a substantial loss in utilization of manpower and capital equipment.

SUMMARY OF THE INVENTION

The apparatus and method for separating capsules as disclosed in this application do not rely on a vacuum principle. Oriented capsules are introduced into a rotor having a passageway adapted for receiving a joined capsule body and cap. The rotor is mounted for selective oscillation whereby its passageway may be selectively connected to a gas supplying means. Sudden introduction of gas into the rotor passageway containing a capsule causes the capsule to be ejected and propelled through a capsule guide means comprising a chute at a high rate of speed. The chute is positioned to direct the capsule into a capsule holder having a shoulder for capturing the cap section. If the body section is the leading portion of the capsule, the momentum it has gained from its high rate of speed will cause it to continue its motion and fully separate from the cap section. Thus, the amount of force available for separating the body section from the cap section is substantially greater than the limited amount gained from a vacuum technique.

2

It is therefore one object of this invention to provide a new and improved apparatus for separating capsule sections. Another object of this invention is to provide a new and unique method whereby capsule sections are readily separated. Another object of this invention is to provide a means for separating capsules which will increase the efficiency and speed of automatic capsule filling equipment.

BRIEF DESCRIPTION OF THE DRAWING

FIG. 1 is a front view of the apparatus of this invention with portions in cross section.

FIG. 2 is an enlarged view in cross section of the apparatus taken at the point where a high rate of speed is imparted on the capsule.

DESCRIPTION OF THE PREFERRED EMBODIMENT

Referring to FIG. 1, capsule separation apparatus 11 may be considered as part of an overall automatic capsule filling unit. Thus, the separation apparatus 11 is coupled to a capsule feeder 12 which orients the capsules into a feeder tube 14. It is noted that each capsule 15 has a cap section 16 and a body section 17. Orientation of the capsules is such that each capsule is introduced into tube 14 with its cap section leading. Tube 14 is connected to a rotor housing 19 which contains a rotor 20. This rotor has a passageway 22 of a diameter that is slightly larger than the diameter of the cap section. A portion 23 of the rotor defining passageway 22 has been beveled or chamfered.

A tube coupling 25 is provided on one side of rotor housing 19. Tube coupling 25 is associated with a gas supply means. Diametrically opposite this coupling is a capsule guide means or chute 27 which extends through housing 19 in communication with the chamber containing rotor 20. Chute 27 comprises a relatively rigid tube of a diameter slightly larger than capsules 15. The exit end 28 of chute 27 is positioned in close relationship with a capsule receiving device 30. Capsule receiving device 30 may be in the form of a rotary disk or a conveyor and comprises a cap section receiving portion 31 and a body section receiving portion 32. Extending through these receiving portions are bores 33 of a well-known configuration adapted for receiving capsules. Thus, the cap section receiving portion 31 of the receiving device, for easy entry of a cap section 16, has an enlarged opening 34 which is connected to a bore 33a having a shoulder 36. Shoulder 36 is of a diameter such that cap section 16 cannot pass therethrough. The body section receiving portion 32 of device 30 has a bore 33b with a length exceeding the length of the capsule body section 17 and a rounded end 38 on which the body section is seated. A small port or vent 40 communicates with the rounded end 38 and a vacuum supply means 41.

In operation, capsules upon being oriented, are fed by gravity or other means, into tube 14 with the cap section first entering the tube. A single capsule is received in rotor passageway 22. A synchronizing device then actuates rotor 20 in a clockwise direction for ninety degrees whereby passageway 22 falls into communication with the gas supply means and its tube 25. The gas supply means may operate in an intermittent fashion and in synchronization with rotation of rotor 20. Thus, as passageway 22 aligns with tube 25, the gas supply means is simultaneously actuated and a short burst of gas, such as air, oxygen or nitrogen, is introduced against the cap section as shown in FIG. 2. The beveled portion 23 of rotor 20 is desirable in order to prevent jamming against the next capsule prior to entry. Thus, as rotor 20 oscillates ninety degrees, it will tend to slightly raise the line of oriented capsules in tube 14.

When the burst of gas hits a capsule in rotor 20 this capsule is propelled outward into chute 27 at a high rate

of speed. The capsule continues its fast motion until its cap section 16 slams into shoulder 36 on bore 33a. However, inasmuch as no interference has yet been made with the travel of body section 17, its momentum will cause continued motion until its end rests against the rounded end 38 of bore 33b. Vent 40 serves to exhaust the amount of air that would otherwise be compressed as body 17 enters into bore 33b. In addition, a venting means or a vacuum supply line 41 may be coupled to vent 40 to further assure exhaustion of air in bore 33b as well as to prevent body section 17 from bouncing upward after it has hit rounded end 38 of the bore. In such a manner momentum of body section 17 has caused it to separate from cap section 16, and thus the two capsule-receiving portions 31 and 32 may be separated for subsequent introduction of medicament into the body section.

The design limits on this means for separating capsules are substantially wide. Thus, the amount of force applied against the capsule in rotor 20 is not severely critical. A gas pressure of 15 pounds per square inch has been found to be quite acceptable. In general, it is only necessary that a sufficient amount of gas pressure be applied to the capsule to impart a rate of speed that will cause the momentum of the body section to separate it from the cap section without damaging either the cap section as it hits shoulder 36 or the body section as it slams into the rounded end 38 of bore 33b.

It is to be understood that modifications of the illustrated apparatus can be made without departing from the spirit of this invention. Thus, capsules may enter rotor 20 with the cap section trailing if rotor 20 oscillates counterclockwise and beveled portion 23 is repositioned on the opposite side of the rotor passageway 22. Rotor 20, although showing only one passageway 22, may have a series of such passageways, with each being linked to a gas supply and a chute. In addition, the internal diameters of chute 27, passageway 22 and feeder tube 14 can be enlarged whereby larger capsules may pass through without the need for changing parts other than the capsule receiving device 30. The force produced on the capsule by the gas supply means can also be developed by applying a hammer element such as a leaf spring against the end of the capsule.

I claim:

1. Apparatus for separating two-piece, hard-shell capsules comprising an element having a passageway adapted for the close reception of a two-piece, hard-shell capsule consisting of a body section telescoped within a cap section, a gas supply means and a capsule guide means with said passageway disposed therebetween and in selective communication with said gas supply means and a first end of said capsule guide means, and a capsule holder having a cap section holder defining a bore juxtaposed on a body section holder defining a bore, said cap section holder bore and said body section holder bore being in communication with a second end of said capsule guide means.
2. Capsule separating apparatus as defined in claim 1 in which said element passageway is in selective communication with a supply source of oriented capsules.
3. Capsule separating apparatus as defined in claim 2 in which said body holder bore is of a predetermined length exceeding the length of said capsule body.

4. Capsule separating apparatus as defined in claim 3 in which said element is a rotor mounted for selective oscillation.

5. Capsule separating apparatus as defined in claim 4 in which selective oscillation of said rotor effects said selective communication of said passageway with said gas supply means and said guide means.

6. Capsule separating apparatus as defined in claim 5 in which said capsule guide means comprises a substantially rigid tube.

7. Capsule separating apparatus as defined in claim 6 in which said supply source of oriented capsules is in selective communication with said rotor passageway for gravity feed of capsules thereto.

15 8. Capsule separating apparatus as defined in claim 7 in which said rotor passageway has a beveled portion adjacent a capsule supply tube connected to said supply source of oriented capsules.

9. Capsule separating apparatus as defined in claim 8 in which a vacuum means is connected to said cap and body holder bore.

10. A method of separating a two-piece, hard-shell capsule having a cap section and body section telescoped therein comprising the steps of:

25 orienting a capsule with its cap section pointing in a predetermined direction, projecting the capsule in said predetermined direction at an initial high velocity, and effecting a reduced velocity on one of said capsule sections whereby the initial high velocity of the capsule imparts a momentum on the other section of a magnitude effecting separation of the capsule sections from each other.

35 11. The method of separating capsule sections as defined in claim 10 in which said capsule is projected at an initial high velocity by a gas supply means.

12. The method of separating capsule sections as defined in claim 11 in which the reduced velocity is effected on the cap section with momentum being imparted on the body section.

40 13. The method of separating capsule sections as defined in claim 12 in which the projection of the body section is halted upon separating from the cap section.

14. The method of separating capsule sections as defined in claim 13 in which the gas supply means effects a sudden burst of force on said capsule.

50 15. The method of separating capsule sections as defined in claim 14 in which the reduced velocity on the cap section is zero and is effected by applying a halting action on the open end of the cap section.
